UNITED STATES PATENT OFFICE

CAREY E. STRAUSBAUGH, OF CHILLICOTHE, OHIO

COAL-CAR STAKE-Straightening DEVICE

Application filed July 5, 1928. Serial No. 290,636.

This invention relates to new and useful improvements in straightening devices for metal bars and has more particular reference to a device for use in the straightening of 5 coal car stakes, the primary object of the invention residing in the provision of a device of this character which may be readily associated with the car body adjacent a bent stake and that may be operated for straightening 10 the stake and this without the necessity of removing the car from the track for removing the stake from the car body.

The invention is further characterized by 5 simplicity of construction and its efficiency of operation and by reason of the fact that the device may be operated for the desired purpose by unskilled workmen.

With the foregoing and other objects in view as the nature of the invention will be 10 better understood, the same comprises the novel form, combination and arrangement of parts hereinafter more fully described, shown in the accompanying drawings and claimed.

In the drawing wherein like reference characters indicate corresponding parts throughout the several views:

Figure 1 is a fragmentary vertical section through a coal car body adjacent the bent stake disclosing my device as associated with 10 the car and in the act of straightening the stake, and

Figure 2 is a detail horizontal section taken substantially upon the line 2—2 of Figure 1, looking downwardly in the direction of the 15 arrows.

Now having particular reference to the drawings A designates generally a conventional coal car body, the side and end walls of which are equipped with the usual 10 strengthening stakes one of which is illustrated in the drawing and designated by the reference character B.

It is of course well known that during the life of a coal car, the stakes will become 15 bulged outwardly due to the unusual weight of the coal within the car. Heretofore it has been necessary to remove the cars from the track or at least to remove the stakes from the body in order to facilitate the straightening thereof. Mostly however, when a stake

becomes bent it is necessary to remove the same and apply a new stake in lieu thereof.

These disadvantages are entirely overcome by the use of a device herein shown and described and claimed. The invention consists 55 of an inverted L-shaped frame 5 preferably constructed of a pair of L-bars arranged in face to face relation and secured in its relation by welding, riveting or the like.

The outer end of the upper horizontal portion of the frame 5 turns downwardly at right angles to provide a finger 6 for hooked engagement over the upper edge of the car wall directly above the upper end of this stake B. In back of this finger 6 the frame is 35 equipped with one or a pair of spaced depending hanger plates 7 to or between which is pivotally arranged a depending elongated lever 8 the same being formed throughout its length with spaced bolt openings 9 so as to 40 facilitate the attachment of a suitable spaced encountering straightening head to any predetermined point with respect thereto.

This head is as more clearly disclosed in Figure 2 pivotally secured to the lever 8 directly intermediate the ends of the bent portion of the stake. The side flanges of the angle bars forming the frame 5 are formed adjacent their lower ends with spaced notches 11 and arranged therethrough and secured to 45 the webs of the angle bars forming the frame by reason of a removable pin 12 by the inner twisted end of metallic tie straps 13—13 that diverge toward the outer ends thereof, the extreme outer ends of these tie straps being 50 provided with reversely bent hooks 14—14 for engagement with the adjacent bottom rail of the car body A more clearly illustrated in Figure 1.

Rigidly secured to the inner face of the 55 vertical portion of the frame 5 intermediate the spaced notches of the angle bars forming said frame is a compressed air cylinder 15 within which is rectilinearly movable a piston 16 the forward end of which projects 60 through the forward end of the cylinder and is pivoted to the lower end of said lever 8.

Leading into the rear end of this cylinder 15 is an air inlet hose 17 and obviously when the device is associated with the car illus-

trated in Figure 1, the admission of air into the cylinder in back of the piston causes the forward movement thereof. The latter action causes the straightening head 10 to be brought into engagement with the bent portion of the stake B so as to bring about the straightening of the stake. The device is shown as being applied to a car of shallow depth.

10 When used in conjunction with a car of greater depth the tie straps 13 will be secured to the lower end of the frame beneath the cylinder.

15 It will thus be seen that I have provided a highly novel, simple, and efficient coal car stake straightening device that is well adapted for all the purposes heretofore designated.

20 Even though I have herein shown and described the invention as consisting of certain detail structural elements, it is nevertheless to be understood that minor changes may be made therein without affecting the spirit and scope of the appended claims.

25 Having thus described my invention, what I claim as new is:

1. In a coal car stake straightening device, a frame unit, means associated with one end of the frame unit whereby to facilitate 30 its attachment to the upper edge of a wall of the car directly above the upper end of the stake to be straightened, means whereby the lower end of the frame may be secured in spaced relation with the car, a cylinder 35 associated with the frame and having a rectilinearly movable piston therein, a lever pivoted at one end to the forward end of the piston rod and at its opposite end to the said frame and a straightening head associated 40 with said lever and adapted to be moved into engagement with the bent portion of the stake when pressure is admitted into the cylinder in back of said piston.

2. In a coal car stake straightening device, 45 an inverted L-shaped member having a finger on the lateral portion thereof for hooked engagement over the upper edge of the car, above the upper end of the car stake, means pivotally disposed on the vertical portion of 50 the L-shaped member having a finger thereon for engagement with the lower part of said car, a lever pivoted at one end to the lateral portion of said L-shaped member, a straightening head arranged on said lever, 55 and power means associated with the other end of said lever for forcing said straightening head into engagement with the bent portion of said stake.

In testimony whereof I affix my signature.
60 CAREY E. STRAUSBAUGH.
